UNITED STATES PATENT OFFICE.

CARL A. KELLOGG, OF BROOKLYN, NEW YORK.

INKING MECHANISM FOR PRINTING PRESSES.

Application filed March 26, 1919. Serial No. 285,338.

To all whom it may concern:

Be it known that I, CARL A. KELLOGG, a citizen of the United States, residing in the city of New York, borough of Brooklyn, county of Kings, and State of New York, have invented a certain new and useful Ink-
ing Mechanism for Printing Presses, of which the following is a specification.

This invention relates to printing presses and while not specifically limited in its application, is particularly adapted to printing machines wherein one member of the printing couple is moved to and from the other to place a form on one member of the couple.

In printing mechanisms of the general character described and claimed in the co-pending applications of John D. Caplinger Serial Numbers 216,675 and 254,162, wherein the form bed of the machine is fixed, and the impression member is movable toward and away from the form, I have found that in order to enable the form to be readily inserted or removed from the machine that it must be retracted to a considerable height above the form bed to allow of the insertion or removal of the form.

In machines of this type, it has been the practice to so construct the operating mechanism of the impression member that said impression member will have a relatively great throw which serves to normally elevate the impression member much in excess of the distance required to allow of the passage of the form rollers between the form and impression member when the latter is in elevated position.

In a machine of this character, it is well understood that the greater the distance which the impression member is required to travel, the slower the speed of operation will be, and it is therefore at the expense of efficiency of operation that the relatively great throw must be provided to allow of the insertion or removal of the form at the sides of the machine.

Moreover, in the type of press referred to, the impression member is usually guided for operation in standards or fixed guides associated with the sides of the machine adjacent the form bed, and, as these members are usually so positioned as to preclude the insertion of the form in the sides of the machine, said form must naturally be introduced into the ends of the machine, either over the ink drum or from the other end of

the machine. As the forms frequently are quite heavy, the lifting of the form over into place onto the bed is to say the least so arduous a task as to render this procedure heretofore practically impossible, especially where the bed is below the platen and the chains etc. are above the face of the bed.

With the foregoing in mind, the object of the present invention is to provide a machine in which the throw of the impression member may be minimized by so constructing the parts of the machine that the form may be readily positioned on, or removed from its bed without requiring such excessive head room as heretofore. Moreover an object, and an important one from a practical standpoint is to provide means whereby a form may be readily inserted in a machine through the employment of a guide table which serves, not only to support the weight of the form but to guide the same into correct position on the form bed, whereby the lifting of the weighty forms onto the bed, over the chains or inking devices is rendered unnecessary.

Further objects of the invention, though not exclusive, are to provide a machine wherein the chains which move the form rollers are positioned below the face of the form bed for the purpose of economizing in head room; a machine wherein the ink drum is stationary and so constructed that the portion thereof, which normally projects above the face of the bed, may be depressed to a position flush with, or below the face of the bed, so as to not interfere with the passage of the form into or out of the machine; a machine wherein the ink drum is movable longitudinally of its axis; a machine wherein the distributor rolls are rotatable circumferentially of the ink drum, for the purpose of better breaking up the ink; a machine constructed in the manner described with a non-rotatable ink drum, so as not to change the speed of the form rollers when they are brought into engagement therewith; a machine wherein the ink drum is of greater diameter at its center than at its ends, whereby the form rollers are caused to contact for their entire length with the ink drum irrespective of the tendency of centrifugal force to throw the center of the rollers outwardly and free from engagement with the drum; a machine wherein an ink plate is positioned on the opposite side of the form bed

80

105

and is extended around the side of the form bed to the very face thereof, so that the form rollers are in contact with said plate until they reach the form, whereby their speed is maintained constant; a machine wherein distributor rolls are associated with the ink drum, and placed diametrically opposite one another to better balance the operation of the distributor rolls, a machine embodying improved means for mounting the ink drum form roller operating sockets and distributor rolls to allow of reciprocating movement of the ink drum and rotation of the distributing and form rolls about the drum; and a removable form table with its supports.

Features of the invention other than those specified will be apparent from the herein-after detailed description taken in conjunction with the accompanying drawings.

In the accompanying drawings I have illustrated one practical embodiment of the invention, but the construction therein shown is to be understood as illustrative only, and not as defining the limits of the invention.

Figure 1 is a side elevation of a fragment of a machine embodying the present invention;

Figure 2 is a section substantially in the plane of line 2—2 of Figure 1;

Figure 3 is a view similar to Figure 1, but illustrating certain operating parts of the mechanism in different positions;

Figure 4 is a section on line 4—4 of Figure 2;

Figure 5 is a section on line 5—5 of Figure 4, showing details of the ink drum;

Figure 6 is an end elevation of the showing of Figure 5;

Figure 7 is an enlarged elevation of one end of the machine illustrating the manner in which the form rollers are supported and carried by the endless chains; and

Figure 8 is a section on line 8—8 of Figure 7.

Referring to the drawings, A designates the frame of the machine which is provided with an upstanding portion in which is mounted for rotation the crankshaft b, adapted to carry and operate the platen B, the lower curved face of which constitutes the impression surface. Mounted adjacent one end of the frame, and supported thereby, is a form bed C, adapted to receive the form F (Figure 8). The form bed is rigidly mounted in the frame and is provided on its opposite ends with movable plates c, which are slotted at c' and screws c² extend through the slots c' and thread into the ends of the form bed. When the screws c² are loosened, the plates c may be dropped down into the position shown in Figures 4 and 8, to allow of the introduction of the form table and the form onto the bed, but, as soon as the form is in place, the plates c may be

elevated to close the ends of the form bed and the screws c² tightened to hold the form in place.

Extending transversely of the frame are shafts D and E, on one of which are mounted sprocket-wheels g, with which are associated endless sprocket-chains g', with which are operatively associated two sets of form rollers G. The sprockets which are associated with the shaft D co-operate directly therewith, but the sprockets which are associated with the shaft E are not secured to the shaft itself, but are mounted on sleeves g² which are journalled for rotation in the frame A, and through which sleeves the shaft E extends. Secured to each sleeve g², exteriorly of the frame, is a gear g³, driven from another gear g⁴ (Figure 1), and, through these driving connections movement is imparted to the endless chains with the result that the form rollers are caused to travel over the form after having been supplied with ink from an ink drum H, and said ink properly distributed over said form rollers by their passage over an ink plate I, positioned below the form bed.

The ink drum H is mounted on shaft E and is preferably in the form of a hollow metallic member, circular in cross section, but, preferably of larger diameter at its center than at its lateral edges, so that said drum may be graphically described as barrel-shaped in contour. Ink is supplied to the ink drum from an ink fountain J in which is partially submerged a fountain roller j, adapted to be rotated by shaft j', to which is affixed a cam j². Associated with the fountain roller j is a ductor or messenger roll K, adapted to normally rest against the fountain roller to receive ink therefrom, but, shiftable at intervals by the cam j² from the position of Figure 4 to the position of Figure 3, for the purpose of applying ink to the ink drum H.

Associated with the ink drum H are a plurality of distributing rolls h, carried by arms h', fixedly secured at h² to the sprockets g, as best shown in Figure 2, so that the arms are rotated with the sprockets, and serve to move the rollers about the face of the ink drum, for the purpose of distributing the ink over the face thereof. When the distributing rolls run at a high speed, the action of centrifugal force tends to warp them outwardly at their centers so that if the drums H were made perfectly cylindrical, the centers of the distributor rolls would not normally engage with the central portion of the drum, and the distribution of ink on the drum would not be efficiently carried out. However, as stated, the drum is made barrel-shaped to compensate for the action of centrifugal force on the distribution rollers, as well as the action of the same force upon the form rollers, and, accordingly, the

rollers will engage with the drum throughout their entire length and efficient distribution and feed to the form rollers is assured.

In order that the distribution of ink over the face of the ink drum may be thoroughly and completely carried out, the drum H is mounted on the shaft E for longitudinal reciprocating movement while being maintained against rotation. This is accomplished by extending one end of the shaft E beyond the outside of the frame as at E' , and affixing thereto a rigid hub e , to which is pivotally connected a yoke l (see Figures 2 and 3). Yoke l has pivotal movement with the hub e , but is so associated with the hub that rotation of the shaft E is precluded. The yoke l forms part of a vibrator arm L pivoted at l' and being provided at its opposite end with a roll l^2 operating in a closed cam slot l^3 formed in a hub l^4 , fixed to the shaft j' which carries and operates the fountain roll. As clearly shown in the drawings, this cam slot is symmetrical and has a constant throw and consequently the ink drum will be reciprocated at a constant speed.

With this construction, it will be apparent that when the machine is operating the fountain roll is rotating, the distributor rolls are rotating about the face of the ink drum, and said ink drum is being longitudinally reciprocated by the vibrator arm L . This vibrating of the ink drum while the distributor rolls are revolving in engagement with the surface thereof results in complete and proper distribution of the ink over the surface of the drum. The drum H is co-axial of the sprockets g , and as a result the form rollers are successively brought into engagement with the periphery of the drum and receive an ink charge therefrom. After leaving the ink drum, the form rollers are carried along beneath the form bed and engage with the ink plate I , which serves to properly keep the form rollers turning. The rear end of the ink plate I is extended upward between the sprockets of the shaft D , as shown at I' in Figure 4, to the very edge of the form bed, so that the form rollers roll on the ink plate until they come to the form bed and pass immediately to the form after leaving said plate. The extension I' is provided with a pivoted portion i' hinged at i , as shown in Figure 7, so that it may swing back in the position shown in dotted lines in Figure 4 to allow of putting on the form from that end also. The advantage of having the form rolls contact with the ink plate I and its extension for so large a portion of their travel, is that the rolls will not change speed after leaving said plate so as to engage with the form at a slower speed which would necessarily cause the rollers to jump when they contact with the form, and cause poor inking.

In order that the form rollers may be properly guided in their passage over the form, the rollers are mounted on the chains g' after the manner shown in Figures 7 and 8 and the chain is provided with rollers m ⁷⁰ which engage with the track m' extending in depressed relation along the edges of the form bed to hold the rollers at a proper height above the bed while additional rollers m^2 are associated with the chains g' ⁷⁵ and engage beneath a track m^3 mounted on the frame, the purpose of which is to hold the rollers to their work. By this construction, the chains run in substantially depressed channels at the edges of the form bed, and are, in a sense, out of the way, or in a more or less concealed position. These curved ends of the guides hold the chains and the form rollers in their proper positions while the direction of their travel is ⁸⁰ being reversed.

In the insertion or removal of the form relative to the machine, said form may be introduced or removed from either end thereof. It is for this reason that the hinged portion i' is provided in the extension of the ink plate I . If the pivoted section i' is moved to the dotted line position of Figure 4, it will allow free access to the screws c^2 , which, when loosened, will allow the locking plate c to drop and permit the table to be placed in position to slide the form longitudinally into the machine and freely from the form bed. In positioning the form in the machine, the pivoted section i' is swung back as shown in Figure 4, and the form table introduced, and the form slid into place after which the plate c is elevated and the screws c^2 tightened to hold the form in place. Thereafter, the section i' may be swung into the closed full line position of Figure 4 wherein its free end will be supported by the plate c .

The machine of this invention provides for the insertion or removal of the form from the opposite end of the machine, and, in order that these operations may be efficiently carried out, the ink drum H is preferably formed with a portion H' of the surface thereof adjustable so that this portion, which normally extends into the path of movement of the form into and out of the form bed, may be lowered, when a change of forms is desired, into the position shown in full lines in Figure 4. To this end, the portion H' has link connections n , (see Figure 5) with a manually operable crank shaft N mounted for rotation in the opposite ends of the drum and provided at one end with an operating handle n' , which may be locked in either of its extreme positions by a pin n^2 adapted to engage with apertures n^3 in the end of the drum. As the handle n' is operated to rotate the crank shaft N , the portion H' of the drum is raised or lowered ¹⁰⁰ ¹⁰⁵ ¹¹⁰ ¹¹⁵ ¹²⁰ ¹²⁵ ¹³⁰

in accordance with the direction of rotation of the arm n' , and said portion H' is guided in its movement by guides n^* formed on the inner surface thereof, and engaging with rods n^5 which extend longitudinally through the interior of the drum.

In the normal operation of the machine, the portion H' is elevated to complete the periphery of the drum, but when it is desired to insert or remove a form, the handle n' is manipulated to depress the portion H' into the position shown in Figure 4, to allow of the positioning in the machine of a table O which may be supported at one end on one of the plates c , and at its other end, on the rod o . The table O is best shown in Figures 4 and 8 and is provided at its lateral edges with upstanding flanges so that a form may be placed on the table and pushed longitudinally thereof directly on to the form bed. A table the full width of the machine may be provided, but I preferably use a table but the width of one form, and through the employment of a table of the appropriate width the form may be readily guided into or out of the machine. It will be understood, that the table is employed only at the time of insertion or removal of the form, and that at other times is removed from the machine to allow of proper operation of the distributor rolls and the form rollers G .

The machine thus provides means whereby a form may be introduced into or removed from the bed from either end of the machine, and while it is possible to introduce the form from the drum end of the machine without making the drum collapsible as described, as by having but a part of a cylinder, for making a flat side on the drum and revolving the drum to bring the flat side up to allow the table to be put in place, it is preferable that the collapsible construction be employed as shown and described. However, the drum may have a hinge part operating after the manner of a hinge z' of the ink plate, or said drum may have a portion of its surface removable so that said portion may be lifted out of machine to allow of the table being brought into position. The provision of the table O is an important one from a practical standpoint as it allows the form to be laid on the outer end of the table and then slid along the table onto the form bed, the table serving to guide the form over the inking devices into correct position. There has heretofore never been any provision made in a machine of this character wherein the platen is above the bed, to readily place the forms on and remove them from the bed. It is within the invention to use the table resting on the ink drum or the upturned end of the ink plate, but this would cause the form when slid to or from the table to bridge as the face of the

table would not be flush and in line with the face of the bed. It is also within the scope of the invention to remove either the hinged part of the ink plate or the movable part of the ink drum.

Having thus fully described the invention, what I claim as new, and desire to secure by Letters Patent is:

1. In a printing press, a form bed, in combination with inking mechanism embodying an ink supply, an inking surface separate from and independent of the form bed, a distributor roller co-operating with said surface, means for rotating said distributor roller to traverse said surface while in engagement therewith, and a ductor roller movable between the ink supply and the inking surface.

2. In a printing press, a form bed, in combination with inking mechanism embodying an inking surface, a non-rotatable shaft supporting said surface, a plurality of sprocket chains, a form roller carried and supported by the sprocket chains, sprockets cooperating with said chains and mounted for rotation co-axially of said shaft, and means for rotating said sprockets.

3. Printing press inking mechanism embodying an inking surface, a non-rotatable shaft supporting said surface, form roller supporting and operating sprockets mounted for rotation co-axially of said shaft, and means for rotating said sprockets.

4. Printing press inking mechanism embodying an inking surface, a non-rotatable shaft supporting said surface, a form roller supporting and operating sprocket mounted for rotation co-axially of said shaft, means for rotating said sprocket, and means for reciprocating the ink surface while it is held against rotation.

5. Printing press inking mechanism embodying a shaft, an ink surface supported by such shaft, a sleeve co-axial with said shaft and supporting the same, and means mounted on the sleeve for operating a form roller while the shaft is maintained against rotation.

6. Printing press inking mechanism embodying an ink drum, an ink supply, a plurality of distributor rollers, means for rotating said rollers around the surface of the ink drum while in engagement therewith, and a ductor roller operable to supply ink to the ink surface from the ink supply once for a plurality of complete rotations of said distributor rollers about the ink drum.

7. Printing press inking mechanism embodying an ink supply, a substantially cylindrical ink drum of greater diameter at its center than at its ends, a distributor roller, and means for rotating the distributor roller around the axis of the drum while in engagement with the circumference of the drum.

8. Printing press inking mechanism embodying an ink supply, a substantially cylindrical ink drum of greater diameter at its center than at its ends, a distributor roller, and means for gyrating the distributor roller around the axis of the drum while said drum is maintained against rotation.

9. Printing press inking mechanism embodying an ink supply, a substantially cylindrical ink drum of greater diameter at its center than at its ends, a distributor roller, and means for gyrating the distributor roller around the axis of the drum while said drum is maintained against rotation, in combination with means for simultaneously imparting axial reciprocation to said drum.

10. An ink drum, for printing presses provided with a larger diameter at its center than at its ends, for the purpose of compensating for the action of centrifugal force on rollers adapted to co-operate with said drum.

11. An ink drum for printing presses which is crowned to render the diameter at its center greater than the diameter at its ends for the purpose of compensating for the action of centrifugal force on rollers adapted to cooperate with said drum.

12. Printing press inking mechanism embodying a form bed, an ink drum, a portion of which normally projects above the plane of the form bed, and means for retracting the projecting portion to a position below the plane of the form bed.

13. Printing press inking mechanism embodying a form bed, and an ink drum separate and independent of the form bed and so formed that all parts thereof will be below the plane of the form bed during the positioning of a form in the machine.

14. In a printing press, a form bed, and inking mechanism embodying an ink drum so formed that all the parts thereof will be below the plane of the form bed during the positioning of a form in the machine, and a table for guiding the form over the ink roller and on to the form bed.

15. In a printing press, a form bed, and inking mechanism embodying an ink drum, a portion of which normally projects above the plane of the form bed, and means for retracting the projecting portion of the ink drum to a position below the plane of the form bed, to allow of the positioning of a table in the machine for the purpose of guiding a form into place upon the bed.

16. Printing press inking mechanism embodying a form bed, an ink drum of greater diameter at its center than at its ends, and so positioned, that a portion of said drum normally projects above the plane of the form bed, and means for retracting the projecting portion to a position below said plane.

17. Printing press inking mechanism em-

bodying a form bed, and an inking surface, a portion of which projects above the plane of the form bed, said projecting portion being hinged for pivotal movement to a position below the plane of the form bed.

70

18. Printing press inking mechanism embodying a form bed, and an inking surface, a portion of which projects above the plane of the form bed, said projecting portion being movable from its projecting position to a position out of the path of a form introduced onto the form bed in the horizontal plane of said form bed.

75

19. Printing press inking mechanism embodying a plurality of ink surfaces, a distributor roller, a form roller, means for rotating the distributor roller over one of said surfaces, and means for moving the form roller over all of said surfaces.

80

20. Printing press inking mechanism embodying a plurality of ink surfaces, a distributor roller, a form roller, means for rotating the distributor roller over one of said surfaces, and means for moving the form roller over all of said surfaces, in combination with means for reciprocating the ink surface, over which the distributor roller rotates, in a direction parallel to the axis of rotation of said roller.

85

21. Printing press inking mechanism embodying an endless chain, a form roller carried by said chain, a stationary form bed, a movable inking surface, rollers and guides cooperating with the chain for substantially the entire length thereof to hold the chain to a predetermined path and cause the form roller to traverse the form and inking surface, and means for reciprocating the inking surface.

90

22. Printing press inking mechanism embodying a curved inking surface, distributor rollers positioned diametrically opposite one another, means for gyrating said rollers about said ink surface while said surface is maintained stationary with respect to the direction of rotation of the distributor rollers, and means for simultaneously reciprocating said surface back and forth at a constant speed in a direction parallel to the axis of rotation of the distributor rollers.

100

23. Printing press inking mechanism embodying an ink drum, and a plurality of distributor rollers mounted for gyration about the axis of the drum, said drum being of greater diameter at its center than at its ends, whereby the rollers are caused to engage throughout their entire lengths with said drum irrespective of the action of centrifugal force.

110

24. Printing press inking mechanism embodying a crowned curved ink surface, and a distributor roller of uniform diameter associated with said surface.

115

25. Printing press inking mechanism embodying an endless chain movable continu-

130

- ously in one direction, a form roller carried by said chain, a form bed, an inking surface mounted independently of the form bed, rollers and guides cooperating with the chain for the greater portion of its length to hold the chain to a predetermined path, means for reciprocating the inking surface in a direction transversely of the path of travel of the chain.
26. Printing press inking mechanism embodying an endless chain, means for continuously moving the chain in the same direction, a form bed, an inking surface positioned at a distance from the bed, a form roller carried by the chain, means for guiding the chain throughout substantially its entire extent, whereby the form roller is held to a predetermined travel to cooperate with

the form bed and inking surface, means for reciprocating the inking surface in a direction transversely of the path of travel of the chain.

27. A printing press embodying a form bed, and a form table flush with the face of the bed and adapted to be supported by the press to facilitate the positioning or removing of a form to or from the bed.

28. A printing press embodying a form bed, and a form table substantially flush with the face of the bed and at least one end of said table being adapted to be supported by the press to facilitate the positioning or removing of a form to or from the bed.

In testimony whereof, I have signed my name to this specification.

CARL A. KELLOGG.
